UNITED STATES PATENT OFFICE

SALVATORE D. TOMASO, OF CHICAGO, ILLINOIS

STREET INDICATOR

Application filed September 27, 1926. Serial No. 138,027.

This invention relates to devices installed in street cars, omnibuses, and like vehicles to indicate to the passengers what crossings are being approached, and its object is to provide a device of this kind which is accurate and dependable in its operation.

A further object of the invention is to construct the same with a gearing which is positive in its operation, eliminating the possibility of variation in the travel of the indicator.

A still further object of the invention is to adapt the same to emergencies and irregularities in the operating schedule of the vehicle.

Another object of the invention is to make its operation so simple that it will require no attention except at the ends of the trips or in the event of irregularities in the operating schedule.

A final, but nevertheless important object of the invention is to construct the same ruggedly and in compact form, whereby it may withstand road vibration and take up a minimum amount of space.

With the above objects in view, and any others that may suggest themselves from the specification and claims to follow, a better understanding of the invention may be had by reference to the accompanying drawings in which—

Fig. 1 is an elevation of the novel indicator;

Fig. 2 is an interior view of the mechanism compartment, showing its application to the street indicating element;

Figs. 3 and 4 are, respectively, sections on the lines 3—3 and 4—4 of Fig. 2;

Fig. 5 is a section of a detail, as taken on the line 5—5 of Fig. 2; and

Fig. 6 is a diagrammatic view of the electrical circuit employed by the indicator.

Referring specifically to the drawings, 10 denotes the casing in which the novel indicator is contained. Like the common fare register, the indicator is hung inside the front end of the car, and carried by the conductor to the opposite end when the car reaches the end of the line and is about to start on the return trip.

In the present showing, the left-hand side of the casing is reserved for the ribbon 11 on which the names of the streets to be indicated are printed, in vertical order; and the right-hand side of the casing contains the mechanism which operates the ribbon. As shown in Figure 1, the frontal panel 10a is glazed and perforated at the center to expose the name of the street being approached; and the panel is also perforated at the sides to expose advertising matter carried by the ribbon alongside the street-name column.

The ribbon 11 is trained on a pair of vertically-spaced spools 12 and 12a, journaled on axles 12b, becoming wound upon one during the course of a trip, and unwound from the same and wound upon the other spool on the return trip. The motion of the ribbon is governed by one or the other of two sprocket rollers 13 and 13a positioned in front of the spools and having their teeth 13b meshing with marginal perforations 11a in the ribbon, as in the case of motion picture film. The spindles of the spools are freely journaled in the left-hand wall of the casing, and a partition 14, but the spindles 13c and 13d of sprocket rollers also extend through the partition to receive motive elements which come into play to rotate one or the other sprocket roller depending upon the direction of the trip.

Beyond the partition 14 is another partition 15, between which and the right-hand wall of the casing is located the power source for the movement of the ribbon 11, in the form of an electric motor 16. The power of the latter passes through a worm and hock-gear combination 17, a vertical shaft 18, a bevel-gear set 19, a horizontal shaft 20, a spur gear 21 and a spur gear 22 to a pinion 23 rotatable on a stub shaft 24 projecting from the partition 14. The pinion 23 has a spur gear enlargement 25 which is in constant mesh with a larger spur gear 26 carried on the pin 27 of an arm 28, the rear end of which is pivoted on the stub shaft 24. One face of the gear 26 carries the ring 29 and pin 30 of a Geneva movement set with which is adapted to selectively actuate either one of two star-wheels 31 and 32, the former being mounted to rotate on a stub shaft 31a of the partition 15.

14, and the latter being mounted on an extension 32a of the sprocket shaft 13d. The star-wheels 31 and 32 are located respectively above and below the ring-and-pin unit 29, 30.

5 Thus, when the arm 28 is in the high position indicated in Figure 3, the upper star wheel—31—receives the effect of the Geneva movement; and should the arm be swung downwardly the connection with the upper star 10 wheel will be severed and a working connection made with the lower one.

The star wheel 31 has a spur gear counterpart 33, with which is meshed a similar gear 34 carried by the sprocket roller spindle 13c; and the star wheel 32 is directly mounted on the continuation 32a of the sprocket roller spindle 13d.

The gearing between the motor 16 and the pinion 23 is incidental, and may be changed 20 for any other gearing which will bring about the speed and power necessary for the mechanism controlled by the said pinion. The provision of the Geneva movement results in the translation of the continuous 25 motion induced by the motor and the incidental gearing into a stop motion by the sprocket roller 13 in the direction of the arrow in Figure 4 when the gears are in the position of Figure 3; and when the arm 28 has 30 been swung downwardly, the connection with the sprocket roller 13 has been broken and a connection made with the sprocket roller 13a, the rotation of the latter being, however, in the reverse direction.

35 The position of the arm 28 thus determines whether the sprocket roller 13 shall rotate with a predetermined stop motion whereby to take on the ribbon 11 while the sprocket roller 13a freely pays it out; or whether the process 40 is reversed at the same rate. The stop motion is obviously geared to display the names of the streets being approached in regular succession through the frontal panel 10a in registration with the opening therein. Also, 45 it will be evident that the provision of the extra gears 32 and 34 for the sprocket roller spindle 13c—instead of mounting the star wheel gear 33 directly thereon—is to secure a motion by the sprocket roller 13 in reverse 50 direction from that imparted to the sprocket roller 13a.

An actuating lever for the reversing arm 28 is provided at 35, being medially pivoted at 36 to the partition 14, and having a link 37 55 near the front end which is attached to the arm 28. The lever 35 is projected forwardly through an opening 10b in the casing panel 10c corresponding to the mechanism compartment, so as to be handily reached for reversing the gearing by hand. The partition 14 also carries a small shelf 38 with an extended leaf spring 39, over which a depending finger 35a of the lever 35 is frictionally 60 movable during the stroke of the lever in one or the other direction. The frictional en-

gagement of the lever with the spring maintains the lever in the position to which set, against accidental departure and consequent premature reversal of the gears.

In order that the above apparatus may render the service anticipated automatically, a series of stops 40 carried by the trolley wire 41 of the railway line are employed to induce the operation of an electrical system diagrammatically illustrated in Figure 6. 75 The stops 40 are so attached to the trolley wire or cross-supports thereof that they do not obstruct the free passage of the trolley wheel; and the spacing of these stops corresponds to that of the streets crossed by the 80 line.

The trolley pole of the car is fitted with a contact switch 42 which is adapted to close momentarily as tripped by each stop 40 during the course of the trip, the switch containing 85 spring or gravity means whereby to break the contact immediately as the stop is passed. Since a trolley wire stop and a make-and-break trolley-supported contact are not new in the art, a detailed description of the representative showing in Figure 6 is not considered necessary. It should be noted, however, that the switch is not in the trolley-wire circuit, but controls a branch of the lamp, pump or other minor circuit in the car. This 90 branch circuit receives its energy by the insertion of a plug 43 into a convenient outlet in the minor circuit.

The element immediately controlled by the switch 42 is a solenoid 44 having a 100 medial tap or terminal in addition to the end terminals. A conductor 45 passes from one terminal of the switch to an end-terminal of the solenoid; a conductor 46 passes from the other terminal of the switch to 105 one terminal of the plug 43; and a conductor 47 passes from the medial terminal of the solenoid to the other terminal of the plug. When the switch is tripped, its momentary closing has the effect of projecting the solenoid plunger 44a outwardly in the direction of the conductor 45, causing a switch arm 48 to close in a receptacle 48a. A circuit is now closed comprising the electric motor 16 (not shown in the diagram, but 110 indicated), a conductor 49 from one terminal of the motor to one terminal of the plug 43, and a return 50 from the other terminal of the plug to the motor. The latter now operates the gearing associated with the indicating ribbon 11, inducing that Geneva movement which is in gear to move through one of its periods and shift the indicating ribbon one section. At this point the star-wheel 32, which acts in unison with the star-wheel 31 through the medium of the positive gearing of the ribbon perforations 11a, trips a spring contact switch 51a in proximity to it, this switch being interposed in a circuit comprising a lead 115 120 125 130

to the other end-terminal of the solenoid 44 and a lead 53 to the plug 43. The effect of the trip-contact of the switch 51a is to cause the solenoid to retract its plunger 44a and therefore break the motor circuit. The motor slows down to a stop. Due to the Geneva movement, the precise stopping time of the motor is immaterial, as the star wheel of the movement will remain still while the ring-and-pin unit 29, 30 continues in motion the greater part of a revolution. The tripping relation of star-wheel 32 with the switch 51a will therefore be such as to occasion the stoppage of the motor well within the idling period of the unit 29, 30. The mechanism is now inactive until the line stop 40 for the next crossing is met; when the operation is repeated.

When the end of the car line is reached, it is my intention to automatically reverse the travel of the indicating ribbon 11. The motor and gears in general will continue to operate as before, but a special mechanism will intercede automatically as the ribbon 25 has fully unwound in one direction to swing the gear-shifting lever 35 as previously described whereby to induce winding motion by that sprocket roller 13 or 13a which until then was idle.

The reversal-actuator comprises primarily a follower hook 54 which rides the ribbon spool 12. When the latter has paid the ribbon out to the end, its periphery discloses a drop or recess 12b into which the follower sinks as clearly shown in Figure 2. As the spool accumulates ribbon, the follower hook 54 rises thereon until the spool is fully wrapped. The sunken and high positions of the follower hook are utilized in the following manner to secure the anticipated gear reversal. The hook 54 is formed into a vertical rod 54a extending in the vicinity of the spools and slidable in a suitable bearing 55. The lower end of the rod 54a is adapted, when the hook 54 is down (as in Fig. 2) to depress and trip a spring-pivoted contact switch 56 ordinarily held open by a spring 56a, and when the hook 54 is up, a side lug 54b of the rod 54a trips a switch 57 similar to the switch 56. The momentary closing of the switches 56 and 57 induces the operation of a solenoid 58 through a circuit similar to that controlled by the trolley switch 42 and 51a in connection with the solenoid 44, whereby the plunger 58a of the solenoid 58 will advance when the ribbon 11 has fully unwound from the spool 12 and recede when the spool has again filled; or, vice versa. The plunger 58a is attached to the reversing lever 35 as indicated at 59 in Figure 3, and the gearing is therefore automatically reversed each time the ribbon has traveled in one or the other direction to the end of its course.

In order that the ribbon as supplied by the

feeding sprocket roller may be taken up by, and closely wrapped on the receiving spool 12 or 12a, these spools are preferably constructed on the order of window-shade rollers, the internal springs 12c thereof, indicated by dotted lines in Fig. 2, being long and of a light gauge for the supply of the slight amount of tension required.

In case a car is late or for some other reason must be switched back before the end of its usual trip, an extension 60 of the motor circuit controlled by a push button switch 61 conveniently located is used. When the button is pressed, the motor begins to operate and the indicating ribbon 11 is caused to travel forward in a rapid series of movements until automatically reversed and in a similar series of return movements until the indication corresponding to the site of the track switch appears, at which point the push button is released and the apparatus resumes its normal operation.

An auxiliary switch 62 to interrupt the conductor 53 may also be provided, for use when the switch 61 is actuated. The opening of the switch 62 makes the repeated action of the switch 51a upon the solenoid 44 ineffective, so that the latter will not become unduly heated or otherwise injured from carrying energy during a comparatively long period.

The novel indicator is thus designed not only for normal operation, but for emergency adjustment subject to the condition peculiar to the operating schedule. The preferred form of the appliance has been described and illustrated, but it should be understood that various minor changes and refinements may be made in the practical development of the invention without departing from the principle thereof; and I wish to include all such changes and refinements as coming within the scope and spirit of the appended claims.

I claim:

1. A crossing indicator for railways comprising parallel spools, an indicating ribbon wound on the latter, feed sprockets geared to the ribbon, a motor geared to the sprockets, a selector in the motor gearing to limit the drive to one sprocket for the propulsion of the ribbon in a given direction and to the other sprocket on the return course, a stop-motion element operative in the drive of the selected sprocket, a road-crossing stop, a cut-in motor switch actuated by the latter, and a cut-out motor switch actuated by the stop-motion element.

2. A crossing indicator for railways comprising parallel spools, an indicating ribbon wound on the latter, feed sprockets geared to the ribbon, a motor geared to the sprockets, a selector in the motor gearing to limit the drive to one sprocket for the propulsion of the ribbon in a given direction and to the other sprocket on the return course, a stop-motion

- element operative in the drive of the selected sprocket, a road-crossing stop, a contact switch tripped by the latter and operative on a solenoid in one direction, a motor switch closed by such operation, and a contact switch actuated by the stop-motion element and operative on the solenoid in the opposite direction to open said motor switch.
3. A crossing indicator for railways comprising parallel spools, an indicating ribbon wound on the latter, a motor, a gearing from the motor to operate the ribbon, a reversing device interposed in the gearing, a follower of the radial accumulation of the ribbon on a given spool, an electromotive element to engage and disengage the reversing device, and switches to control said electromotive element, said switches being actuated with a tripping stroke by the follower in its extreme positions.
4. An operating mechanism for a legend-bearing ribbon in a street indicator, comprising a motor, independent forward and reverse drives for said ribbon, a driven Geneva-movement element in each of said drives, and a Geneva-movement drive element geared to said motor and selectively applicable to said driven elements to operate the same with a stop-motion.
5. A crossing indicator for railways comprising a switch incident to the crossing, an indicating ribbon, a motor, a gearing from the motor to operate the ribbon, a solenoid with a medial tap, a switch for the motor controlled by the movements of the solenoid plunger, a circuit of the tap and one terminal of the solenoid controlled by said first-mentioned switch for the closing of the motor switch, an auxiliary switch actuated by the ribbon-operating gearing, and a circuit of the tap and the other terminal of the solenoid controlled by the auxiliary switch for the opening of the motor switch.
6. A crossing indicator for railways comprising a switch incident to the crossing, an indicating ribbon, a motor, a gearing from the motor to operate the ribbon, a solenoid with a medial tap, a switch for the motor controlled by the movements of the solenoid plunger, a circuit of the tap and one terminal of the solenoid controlled by said first-mentioned switch for the closing of the motor switch, an auxiliary switch actuated by the ribbon-operating gearing, a circuit of the tap and the other terminal of the solenoid controlled by the auxiliary switch for the opening of the motor switch, extensions of the motor switch terminals, and a hand-operated switch adapted to bridge such extensions.
7. In a device of the class described, a rotatable, intermittent stop motion indicator driving means, actuating means therefor, cut-off means for said actuating means, and an element of said indicator driving means having circumferentially arranged projec-

tions adapted to engage and actuate said cut-off means.

8. In a device of the class described, a rotatable intermittent stop motion indicator driving means, actuating means for such driving means, cut-off means for said actuating means, and automatically operated means for actuating said cut-off means at each stop of said indicator driving means, said automatically operated means having circumferentially spaced projections engageable with said cut-off means.
9. In a device of the class described, indicator driving means and including a stop motion gear, actuating means for said driving means, a cut-off for said actuating means, and said stop motion gear having a portion adapted to engage and actuate said cut-off means at the end of each period of movement of said gear.
10. The combination set forth in claim 9, said cut-off means being yieldable and constituting a temporary stop abutment for said stop motion gear.
11. In a device of the class described including rolls, an indicator ribbon wound on said rolls, separate drive means operatively engaged with said ribbon and adapted to be driven in opposite directions, drive gearing selectively engageable with said ribbon drive means, actuating means for said drive gearing, cut-off means for said actuating means, and one of said ribbon drive means having a portion adapted to engage and actuate said cut-off means.
12. In a device of the class described, a ribbon, rolls upon which said ribbon is wound, independent drive elements operatively engaging said ribbon for actuating the same in opposite directions, a driven shaft, an arm swingably carried by said shaft, a gear carried by said arm and having a driving connection with said shaft, said arm being movable to bring said gear into driving connection with said ribbon driving elements, a lever pivoted to a support, a link connection between said arm and lever, and means carried by said support and tending to maintain said lever in a position to keep said gear in selective engagement with a ribbon driving element.
13. The combination set forth in claim 12, and including driving means for said shaft, and cut-off means for said driving means actuated by one of said ribbon driving elements.

In testimony whereof I affix my signature.
SALVATORE D. TOMASO.
